(Cl. D38—6)

To all whom it may concern:

Be it known that we, Matthew R. Grandon and Bruce Burns, citizens of the United States of America, residing in the city of Beverly Hills, county of Los Angeles, State of California, and city of Los Angeles, county of Los Angeles, State of California, respectively, have invented a new, original, and ornamental Design for a Leash Reel Housing, of which the following is a specification, reference being had to the accompanying drawing, forming a part thereof.

Fig. 1 is a plan view of a leash reel housing embodying our novel design;

Fig. 2 is an elevational view thereof; and

Fig. 3 is a sectional view taken on the line 3—3 in Fig. 2.

We claim:

The ornamental design for a leash reel housing, substantially as shown.

MATTHEW R. GRANDON.
BRUCE BURNS.
